UNITED STATES PATENT OFFICE.

OLIVER O. APP, OF NEW YORK, N. Y.

EXCAVATING-MACHINE.

1,290,479.

Specification of Letters Patent.

Patented Jan. 7, 1919.

Application filed February 20, 1911, Serial No. 609,610. Renewed May 31, 1917. Serial No. 172,103.

To all whom it may concern:

Be it known that I, OLIVER O. APP, a citizen of the United States, residing at New York city, in the borough of Manhattan and State of New York, have invented certain new and useful Improvements in Excavating-Machines, of which the following is a full, clear, and exact description.

This invention relates to trenching and excavating machines and more particularly to appliances of this character which are intended to trench through or excavate hard earths or rock, as well, of course as sand and lighter earths.

15 One object of my invention is to provide a novel mechanism comprising rotatably mounted and preferably power driven tools which are adapted to co-act with interposed buckets or the like in such manner that while the said tools serve to disintegrate or break up hard matter to be removed, the buckets will substantially simultaneously scrape or scoop up such disintegrated and other softer material and remove the same from the cut.

20 Another object of my invention is to provide means in a mechanism of the foregoing type for individually driving said tools.

25 A further object of my invention is to provide means whereby the individual driving means for said tools will mutually co-act and aid each other in operation.

30 A still further object of my invention is to so mount the novel trenching and excavating parts of the said mechanism that the same may be swung up or down and laterally to vary the size and shape of the cut, without necessitating a change in location of the principal supporting parts of said mechanism.

35 I further purpose to adapt the said supporting parts and hence the excavating parts for translation along a track or the like and to provide means for locking such parts against inadvertent displacement.

40 These and other objects of my invention will be hereinafter referred to and more particularly set forth in the appended claims.

45 Referring to the drawings which form a part hereof; and in which like references designate like parts:

Figure 1 is a side elevation of a machine constructed in accordance with the principles of my invention.

50 Fig. 2 is a plan of said machine.

Fig. 3 is a section taken substantially on line III—III of Fig. 2.

Fig. 4 is a partial section taken on line IV—IV of Fig. 1; the lateral arms being shown partly in full.

Fig. 5 is an elevation of a modified form of the tool carrying wheel, the same being broken away at the center and the periphery to show pressure fluid connections.

Fig. 6 is a section of another modified form of said wheel similar to section IV.

Fig. 7 is a detail section taken substantially on line VII—VII of Fig. 6, the connecting rod eccentric and guide box being shown in full.

Fig. 8 is a detail section taken on the line VIII—VIII of Fig. 7.

Considering first the construction exemplified in Figs. 1 and 2, the appliance therein shown comprises a car 1, suitably mounted on wheels 2, and adapted to run on the track 3. Standards 4 are preferably disposed at each of the forward corners of this car and these standards are connected at their upper extremities by a yoke 5, while the corresponding rear standards 6 are disposed upon either side of the car somewhat back of the center line thereof, and are correspondingly yoked or connected together by the yoke 7.

A cross member 8 unites the upper portions of yokes 5 and 7 and suitable guys 9, one of which is upon either side of the machine, are connected at their upper extremities to the rear end of the connecting member 8 and extend outwardly and downwardly toward the rear corners of the car, being pivotally connected thereto at 10. Turnbuckles 11 are preferably provided in these guide rods so that they may be placed under proper tension.

The foregoing elements constitute a rigid frame for supporting the operative parts of the device. At the forward extremity of the car substantially on the center line thereof, a bearing 12 is provided and a corresponding bearing 13 is formed directly thereabove in the center of the yoke 5.

These bearings are adapted for the reception of trunnions carried by a massive O-shaped frame 14. Forwardly extending from either side of this frame are brackets 15 which are journaled on their outer face for the reception of a shaft 16, suitable caps 17 carried by the said brackets holding such shaft in position.

As shown in Fig. 2 the greater portion of the frame 18 is substantially oval,

90

95

100

105

110

but the forward extremity thereof is constituted by arms 19, the free extremities of which are proximate each other in the manner shown. The rear end of frame 18 is 5 substantially arcuate and is provided with a series of teeth 20 which are adapted for engagement with a worm 21 so that this portion of the said frame virtually constitutes a worm gear. The worm 21 is secured to a 10 shaft 22 in any suitable manner, and the said shaft is disposed within two short hollow shaft sections 23, which latter in turn are journaled in suitable bearings 24 which form a part of a movable cradle or housing 15 25. This housing consists of a platform 26 and up-standing somewhat triangularly shaped sides which project upwardly from either side of said platform. Forwardly extending from these sides and preferably integrally united therewith, is a frame 27. This frame carries four rollers 28, two upon either side thereof, which rollers are adapted to engage the respective flanks of the worm gear aforesaid. Two sets of guide rollers 29 20 are correspondingly adapted for engagement with flanges which project from the sides of a pair of arcuate racks 30, which racks are disposed substantially midway between the standards 4 and 6, the upper extremities of said racks being preferably integrally united to the yoke 5 upon either 25 side of the bearing 13 therein, while the lower extremities of the racks are fixedly secured to the forward end of the car. Pinions 31 are securely mounted upon the hollow shafts 23 and positioned for engagement with the respective racks 30, so that the housing and correspondingly the worm gear may be raised and lowered by rotating 30 said pinions, and of course, when the said worm gear is elevated, for example, the arms 19 which form the other extremity of frame 18 will be correspondingly depressed. Two motors are carried by housing 25, one, 35 40 45 50 being adapted to drive the worm 21 by means of a pinion 33 carried by the motor shaft, and a gear 34 which meshes therewith and which is mounted upon one extremity of the shaft 22; while the second motor 35 correspondingly drives the pinions 31 by means 55 60 65 of a pinion 36 mounted upon the extremity of its motor shaft which meshes with a gear 37 mounted upon the counter-shaft 38 which is journaled in the sides of the housing aforesaid. This counter-shaft carrying upon either extremity thereof a pinion 39. The respective short hollow shafts 23 each carry a gear 40, said gears respectively being in mesh with the pinions 39, so that when motor 35 is driven in one direction or the other, pinions 31 will be correspondingly rotated clockwise, or counterclockwise, as the case may be, and the housing and the worm gear aforesaid raised or lowered in the manner described.

The shaft 16 carries centrally disposed thereof a sprocket 41 which in this instance is provided with four teeth, said sprocket being adapted for engagement with pins 42 of the flexible element, in this instance the 70 chain 43. A motor 44 is mounted upon a suitable bracket 45 which depends from the frame 18, said bracket being integrally united to the inner side of the worm gear which forms a part of said frame. The 75 shaft 46 in this motor is disposed substantially parallel to the frame 15, and the outer extremity thereof is journaled in an auxiliary bracket 47 which is carried by the corresponding arm 19. Shaft 46 carries a worm 80 85 90 95 48, which drives a worm gear 49, and thereby the shaft 16, so that when motor 44 is operated, the chain 43 may be continuously driven in one direction. In this instance sprocket 41 is driven counter-clockwise, as viewed in Fig. 1. Chain 43 comprises as elements thereof a series of scraping devices, in this instance the buckets or scoops 50, the purpose of which will be hereinafter referred to, and the said chain passes around a large tool-carrying sprocket wheel 51. Various forms of this wheel and of the tools carried thereby, and means for actuating said tools, may be employed, and I have shown several such forms in the accompanying drawings.

Considering first the embodiment of my invention shown in Fig. 1, the teeth of the sprocket wheel therein are apertured for the reception of reciprocable tool shanks 52, upon the outer extremity of which shanks are mounted tools 53, which in this instance consist of base plates or caps 54, each of which is provided with a series of out-standing or projecting points or teeth 55, adapted to gouge into the surface to be cut or disintegrated. As shown in Fig. 7, the plates 54 are preferably recessed for the reception of the head 56 of the shank 52, each plate 54 being secured to the corresponding head 56 by means of bolts 57, and in order to insure a certain amount of flexibility in the tool, I provide helical springs 58 between the washers 59 which are mounted upon the said bolts and the head 56. The teeth or 100 105 110 115 120 125 130 tool points are preferably made removable so that they can be readily replaced when worn, and to this end may be formed substantially as shown in Fig. 7 with heads 60 which prevent the tool points from slipping or jarring out of their respective places.

The inner extremity of each shank 52 is enlarged to form a cross-head 61, which is reciprocably mounted in a recess 62 formed within the teeth of the sprocket wheel 51. Each cross-head 61 carries journaled therein a pin 63 which passes through an eye 64 which forms the outer extremity of a connecting rod 65, these latter each having an eccentric 66 at its inner and eccentric-strap-

forming extremity which serves to convert the rotary motion of the shaft upon which said eccentric is mounted, into reciprocatory movement. These eccentric-bearing shafts 5 are of two lengths which have been respectively designated 67 and 68, the former being the longer and bearing an eccentric upon either end thereof and the latter having its eccentric centrally disposed thereon.

10 The teeth of the sprocket wheel 51 are staggered so that, in the exemplification shown, a single centrally disposed tooth 69 alternates with two teeth 70, disposed adjacent either edge of the wheel. By reason 15 of this arrangement the tools, which are also staggered in corresponding fashion and may be made of different widths, are adapted to cover a cut substantially equal to the width of the face of the tool sprocket. 20 In Fig. 4 the eccentric gearing shafts 67' and 68' are shown as being driven by electric motors, the motor shafts being, in this instance, identical with shafts 67', or 68', as the case may be.

25 The distance between teeth 70 is sufficient to permit of the application of a motor 71 between the eccentrics corresponding to such teeth, which motor is mounted directly in the web 72 of the wheel 51; but where the eccentric is centrally disposed upon its shaft as in the case of the teeth 69, a motor 73 is, 30 preferably in each instance, arranged to one side of such eccentric; motor 73 being directly secured to the inner face of the 35 rim of the sprocket. The outer extremity of each motor shaft 67' is journaled in a lug 74 which projects inwardly from the sprocket rim; sufficient space being afforded between said lug and the corresponding eccentric to permit of a pinion 75 being 40 mounted on said shaft.

In like manner, upon either side of each motor 71 is a pinion 75, this pinion being disposed upon shaft 68' immediately inside 45 of the eccentrics mounted thereon.

All pinions 75 are secured to their respective shafts and all of such pinions upon one side of the sprocket web are in mesh with a common gear 76, those upon the other side 50 of said web being in mesh with a second gear 76, so that in effect while all of the eccentric bearing shafts are individually driven, they are also geared together and their respective motors interact and coöperate to the end that a very uniform running 55 of said motors is obtained.

The center of the web 72 has a bearing 77 formed therein which is bushed as at 78 to form a ball-race, a plurality of balls 79 60 being disposed between such bush and a second bush 80 which is mounted upon a short shaft 81. On either side of the hub of the sprocket wheel through which extends the bearing 77, is mounted a sleeve 82 which 65 co-acts with a corresponding sleeve 83 to

form ball recesses upon either side of the web 72. Balls 84 being disposed between such sleeves and the bushings 83 being inset into the hubs 85 of the respective gear wheels 76, above referred to. Upon the respective 70 opposite sides of each of these gears is a second and smaller hub 86 which is keyed as at 87 to the shaft 81 so that the gears 76 may at all times rotate together.

The free ends of the arms 19 are bushed 75 as at 88 to provide ball bearings or the like for the hubs 86 of the gears aforesaid, auxiliary bushings or sleeves 89 being provided around such hubs and balls 90 being disposed between bushings 88 and 89. It will 80 thus be seen that the gears 76 are frictionlessly journaled in the extremities of the arms 19, while the tool sprocket is in turn carried by the shaft 81 to which these gears are keyed, said sprocket being free to rotate 85 thereupon. It is evident from the construction shown that the motors 71 and 73 in addition to driving the tools in the manner aforesaid, react on the tool sprocket and tend to rotate the same so that even though 90 no separate means be provided for driving the chain 43 there is still a strong tendency for this chain to advance in the manner described, the direction of rotation of motors 71 and 73 of course being adapted to 95 this end. I prefer, however, to provide separate means which may also be termed auxiliary means, in this instance, for rotating the tool sprocket, which means of course is, in this case, the motor 71 and gear therefrom to the sprocket 41 aforesaid. One of the principal advantages derived from the construction herein exemplified is that while 100 a tool is directly driven by a motor, when such tool is not doing work, the motor thereof will aid in the operation of the tools that are doing work at such moment. Further, if for example the motors 71 and 73 be driven at a speed of one thousand revolutions per minute, the tools will thereby be 105 reciprocated at a corresponding rate and will strike the rock, or the like, against which they are driven, a series of forceful blows at the said rate. But it is evident that each 110 of such motors, were it not for the interconnecting means, in this instance the gear system provided, would alternately have a considerable load thrown upon it during one part of each revolution, and would have substantially no load during the other part of 115 said revolution. The interconnection by means of gears, for example, of such motors, obviates this objectionable feature, and the load on such motors is hence substantially uniform at all times when the machine is 120 in operation, if the character of the material to be cut is uniform. The tools of the character in question tend to strike a slightly glancing or wiping blow by reason of the 125 advance of the tool over the surface to be 130

cut due to the rotation of the sprocket 51, and as these blows are delivered forcefully and in very rapid succession, a powerful disintegrating effect is obtained, and the 5 surface of a rock, or the like, against which the tools may be driven, will be rapidly abraded. Substantially simultaneously acting mucking devices, *i. e.* the buckets 50, which are each provided with a sharp cutting edge, scrape over the surface operated upon and collect all loose and also all friable matter, thus clearing away the debris from the tools and continually exposing fresh surface for them to operate upon.

15 In Fig. 6 I have shown a modified form of tool sprocket and drive for the tools, in which but a single motor 91 is employed for driving the co-operating tools, such motor being mounted upon a shaft 92 which is 20 keyed at either end thereof to a hub 93 of a gear 76'; two of such gears being provided as in the foregoing, these gears being correspondingly adapted for engagement with pinion 75 mounted upon shafts 67-68.

25 These shafts by means of eccentrics and connecting rods 65 operate the tools 53. The shafts 68 are in this instance journaled as at 94 in the web of the sprocket wheel, and this web is secured in any suitable manner 30 to the casing of the motor 91, while the said casing is further journaled into recess 95 formed in the bodies of the gears 76', balls 96 being provided therebetween so that in effect the gears 76' may be said to be journaled upon the motor casing. The hubs 93 of gears 76' carry thereon bushings 96' which are journaled in corresponding bushings 97 disposed in the free extremities of the arms 19, any suitable form of bearing of 40 course being usable to this end. The motor casing is secured in any suitable manner to the web 97 of the sprocket so that when the motor 91 is driven, the gears 76' will rotate in one direction, while the sprocket 51 will 45 correspondingly rotate in the other. By this action, through the instrumentality of the pinions 75, the tools 53 will be operated substantially as in the foregoing.

It will thus be seen that this portion of 50 the apparatus may be driven either from a single motor or a plurality of motors, but I prefer the form of device shown in Fig. 4, since this form is adapted to be operated with less friction and a greater amount of 55 power is available for a sprocket of given size.

In Fig. 5 I have shown still another form of tool carrying sprocket, and also a different form of tool. In this instance the 60 sprocket has been shown as being driven by a chain 43, and the teeth 98 of said sprocket carry tools 99 preferably disposed at an angle therein; the tools in this exemplification of my invention being pneumatically operated, fluid pressure being delivered thereto

65 by a fluid conduit 100 extending along or through one of the arms 19, said conduit delivering into a circular groove 101 formed around the axle 102 of the sprocket wheel 103; a plurality of conduits 104 extending outwardly therefrom to the respective tools. If air be delivered through only one arm 19 and it be desired to deliver the same to conduits 104 upon the opposite side of the sprocket wheel to that shown in Fig. 5, the 70 shaft 105 may be centrally apertured as at 106 and ports or conduits 107 may extend radially outward from said aperture so as to open the same to grooves 101 which may be upon either side of the wheel.

75 80 While I have shown mechanically and pneumatically operated tools, it is of course to be understood that any suitable form or type of tool may be employed, and it is obvious that any suitable motive power may be employed therefor.

The general operation of the machine is as follows: Motor 44 co-acts with motors 71 and 73 or with motor 91 according to which form of construction is used, to continually 90 drive the tool carrying sprocket and to drive the bucketed chain. The tools are driven in any of the foregoing ways, and the sprocket 51 may be raised or lowered while in action by means of motor 35. A suitable braking 95 apparatus 108' serves to prevent vertical displacement of the tool sprocket when such motor is not in action. Correspondingly, the motor 32 serves to swing the said sprocket laterally in either direction. The 100 buckets deliver the collected loose material to a chute 108, which delivers said material to a belt conveyer 109 of any suitable description, a portion of which latter is preferably disposed beneath the floor of the car 105 1 and carried thereby, this conveyer serving to raise the debris and deliver the same to a cart or any other suitable receptacle by reason of the oblique extension 110 on said conveyer which projects upwardly and rearwardly from the car. This conveyer may be driven by a suitable motor 111, and may be 110 of any ordinary construction.

The novel mechanism herein disclosed is particularly well adapted for trenching, but 115 is equally well adapted for tunneling or other excavating purposes, and it will be observed that when tunneling, substantially one-half of the tools carried by the tool carrying member, *i. e.* the sprocket 51, will be 120 in operation at practically all times.

As the upward travel of the tools and buckets or muckers tends to react upon the tool carrying sprocket to depress the same, such tendency together with the like tendency due to the action of gravity upon the over hanging parts may be counteracted by the provision of a suitable rail engaging or clamping device such as that shown at 112, which may consist, for example, of a bracket 130

113 supported from the under side of the car; said bracket having a flange 114 at its lower extremity, adapted to bear against the under side of the head of the rail.

5 Having described my invention what I claim is:

1. In an excavating machine, a wheel, a plurality of tools mounted in staggered relationship around and projecting outwardly 10 from the peripheral surface of said wheel, means for rotating said wheel, scraping means adapted to travel substantially in the wake of said tools, and separate means for directly driving said tools.

15 2. In an excavating machine, a chain provided with scraping appliances, sprockets about which said chain is disposed, reciprocable tools mounted in recesses in the teeth of one of said sprockets, separate driving 20 means for directly operating each of said tools, and means for inter-connecting said plurality of driving means.

25 3. In an excavating machine a revoluble structure, a plurality of tools mounted thereon, separate driving means for directly operating each of said tools and means for transmitting power from one of said driving means to a tool operated by another, to thereby aid the latter in its work.

30 4. In an excavating machine, a revoluble member, a plurality of separate power mechanisms spaced around adjacent the peripheral surface of said member and tools carried by said member, operable by said mechanisms and scraping means adapted to travel substantially in the wake of said tools, said tools and scraping means projecting out from said peripheral surface, said tools projecting beyond said scraping means.

40 5. In an excavating machine, a revoluble member, a flexible structure disposed therearound and movable therewith, a plurality of separate power mechanisms spaced around said member, tools operable by said mechanisms, and means for removing relatively 45 loose material from the path of said tools.

50 6. In an excavating machine, a revoluble member, a flexible structure disposed therearound and movable therewith, a plurality of separate power mechanisms around said member, tools operable by said mechanisms, and means carried by said flexible structure for removing relatively loose material from the path of said tools.

55 7. In an excavating machine, a toothed revoluble member, tools movably mounted in

the teeth, power mechanism for moving the working surfaces of said tools toward and from surfaces of said teeth of said member, a chain adapted to engage said teeth and 60 means for driving said chain and member.

8. In an excavating machine, a toothed revoluble member, tools movably mounted in the teeth of said member, a chain adapted to engage said teeth and means for driving said 65 tools, chain and member, the driving means for said tools including power mechanism for moving the working surfaces of said tools toward and from surfaces of said teeth.

9. In an excavating machine, a tooth revoluble member, tools movably mounted in the teeth of said member, said tools being adapted for forcible impact upon a surface to be operated upon, means for violently impacting said tools against said surface, a chain 75 adapted to engage said teeth, scraping means carried by said chain, and means for driving said chain and member.

10. In an excavating machine, a car, a frame, sprockets carried by said frame, a 80 bucketed-chain disposed around said sprockets, and reciprocatory tools mounted in the teeth of one of said sprockets.

11. In an excavating machine, a wheel, a plurality of reciprocatory tools movably 85 mounted around and projecting outwardly from the peripheral surface of said wheel, means for rotating the wheel, scraping means adapted to travel substantially in the wake 90 of said tools, and means for separately driving said tools against the material to be operated upon.

12. In an excavating machine, a plurality of members united to form a chain, a revoluble member about which said chain is disposed, collecting devices carried by some of said first named members, and a reciprocating tool carried by said revoluble member.

13. In an excavating machine, a chain provided with scraping appliances, sprockets about which said chain is disposed, tools movably mounted in recesses in the teeth of one of said sprockets, separate driving means for directly operating each of said tools, and means for interconnecting said plurality 105 of driving means.

In witness whereof I subscribe my signature in the presence of two witnesses.

OLIVER O. APP.
